CLAIM

The ornamental design for a handle for cookware, as shown.

DESCRIPTION

FIG. 1 is a perspective view of a handle for cookware showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view being a mirror image thereof; and, FIG. 7 is a perspective view thereof, the broken line showing of a pan is environmental only and forms no part of the claimed design.

FIG. 1**FIG. 2****FIG. 3****FIG. 4****FIG. 5****FIG. 6**

FIG. 7
